UNITED STATES PATENT OFFICE.

FRANK L. FURBUSH, OF WESTFORD, MASSACHUSETTS, ASSIGNOR TO C. G. SARGENT'S SONS CORPORATION, OF GRANITEVILLE, MASSACHUSETTS, A CORPORATION OF MASSACHUSETTS.

FEEDING MECHANISM FOR PICKERS OR OPENERS.

Application filed February 19, 1924. Serial No. 693,950.

To all whom it may concern:

Be it known that I, FRANK L. FURBUSH, a citizen of the United States, residing at Westford, in the county of Middlesex and 5 State of Massachusetts, have invented a new and useful Feeding Mechanism for Pickers or Openers, of which the following is a specification.

This invention relates to the feeding of 10 fibrous material to a picker or opener for preparing the fiber. As heretofore constructed the feed has usually consisted of a conveying apron and rolls which operated at a constant speed. Sometimes the picking 15 cylinder draws a hank of fiber in without its being disintegrated and it results in an uneven product and sometimes the clogging of the machinery.

The principal object of this invention is 20 to provide means whereby if the cylinder does pick up a long hank or bunch of fiber at its forward end, it cannot feed it all in rapidly but it will be held back by the feeding mechanism itself, pulled out, and 25 thus partly opened up.

Other objects and advantages of the invention will appear hereinafter.

Reference is to be had to the accompanying drawings, in which—

30 Fig. 1 is a side view partly in longitudinal section of a picking machine with a preferred embodiment of this invention applied thereto;

35 Fig. 2 is a view of the feeding mechanism for a similar machine showing a modification; and

Fig. 3 is a similar view showing another modification.

I have shown the invention as applied to 40 a picker having a picker cylinder 10. Under ordinary circumstances the fibrous material is fed in by a single apron conveyor as 11 set up near enough to a set of rolls 12 to feed the material to them. If there is a 45 bunch or hank on this apron as soon as the forward end is engaged by the teeth on the picking cylinder they will pull it right through without its being opened up or separated in any way and it speeds up the 50 rolls 12.

According to this invention the apron 11 is considerably shortened and between it and the rolls 12 are placed two aprons 13 and

14, one above and the other below the line of material passing to the rolls 12 and in 55 position to receive the same from the feed apron 11. Adjustable springs 15 are provided for regulating the space between the two aprons 13 and 14. The principal feature of these aprons is that they are provided with teeth 16 and that these teeth extend rearwardly and not forwardly. They do not assist very greatly in the feeding of the material as that could be fed by smooth aprons. Their part is to hold it back. 60 These aprons are driven by means that is common and therefore not shown and operated at a constant speed. Therefore if the picking cylinder pulls along a hank or bunch of fiber at its end it cannot speed 65 up the aprons 13 and 14 and, in fact, the teeth on these aprons hold the rear end of this bunch of fiber so that it will be pulled out in the space between these aprons and the cylinder. 70

This therefore assists the opening operation of the picker or opener and renders its product much more uniform so that the subsequent processes can take place more evenly. 75

In the form shown in Fig. 2 the parts above described are all shown except that the rollers 12 are omitted and the aprons 13 and 14 feed directly to the cylinder 10. In this case the teeth 16 are shown more in 80 detail, being mounted on strips 18 located transversely on the aprons. 85

In Fig. 3 the conditions are substantially the same except that the upper apron 14' extends beyond the end of the lower apron 90 13 and in line with the latter is a positively driven roll 19 having backwardly projecting teeth on its surface for feeding the material directly to the picker cylinder. 95

In all these forms and in whatever form the invention may be embodied the feed of the material is improved because long bunches of it are opened out in the course of feeding it to the picker or opener and cylinder. 100

Although I have illustrated and described only three forms of the invention I am aware of the fact that other modifications can be made therein by any person skilled in the art without departing from the scope 105 of the invention as expressed in the claims.

Therefore I do not wish to be limited to all the details of construction herein shown and described, but what I do claim is:—

1. The combination with an opening or picking means, of a pair of feed belts for feeding the fiber thereto, said feed belts being operated positively and having a space between them for receiving the fiber, and teeth on both of said belts projecting 10 backwardly at their points of engagement with the stock to prevent too rapid feed thereof.
2. The combination with a machine for opening out fibrous stock comprising a 15 toothed cylinder, of a feed belt for receiving the stock thereon, a pair of feed belts spaced apart, one above and one below the line of stock and in position to receive stock from the first named feed belt between 20 them, said pair of belts having teeth on

their surfaces projecting rearwardly at an angle to the belts into the stock as it is being fed and being located in position to deliver the stock to the cylinder.

3. The combination with a picker having 25 a toothed cylinder, of a feed belt for receiving the stock thereon, a pair of feed belts spaced apart, one above and one below the line of stock and in position to receive stock from the first named feed belt between 30 them, said pair of belts having transverse rows of teeth on their surfaces projecting rearwardly at an angle to the belts into the stock, and rotary means between the pair of belts and the cylinder for assisting in feeding the stock from the belts to the cylinder.

In testimony whereof I have hereunto affixed my signature.

FRANK L. FURBUSH.
